UNITED STATES PATENT OFFICE.

JULIUS ERYC ADAIR, OF GATLIFF, TENNESSEE.

RAILWAY-SIGNAL.

No. 817,685.

Specification of Letters Patent.

Patented April 10, 1906.

Application filed October 6, 1905. Serial No. 281,624.

To all whom it may concern:

Be it known that I, JULIUS ERYC ADAIR, a citizen of the United States, residing at Gat-
liff, in the county of Campbell and State of
Tennessee, have invented a new and useful
5 Railway-Signal; and I do hereby declare the
following to be a full, clear, and exact de-
scription of the invention, such as will enable
others skilled in the art to which it apper-
tains to make and use the same.

This invention relates to an attachment
for semaphore train-order board or signal sys-
tems of the usual construction which con-
sists merely of a telltale—that is, a device
15 which an operator is supposed to turn down
to cover the fastening means that holds the
signal in the proper place—which will prohibit
him from pulling a signal when he has orders.

The object of the invention is to provide a
20 device of this character which will prevent an
operator from forgetting an order in case he
has one for a train when that train blows for
his signal. Heretofore there has been nothing
25 to prevent the operator from forgetting
to place the signal in correct position. That
being the case, the operator through mistake
would pull the signal for a train for which he
had orders, thereby running two trains to-
30 gether. Thus this device obviates this
trouble.

This invention comprises further objects
and combinations of elements, which will be
hereinafter more fully described, and shown
35 in the accompanying drawings, and the novel
features thereof will be particularly pointed
out by the appended claims.

To obtain a full and correct understanding
of the details of construction and combination
40 of features, elements, and advantages, refer-
ence is to be had to the hereinafter set forth
description in connection with the accompa-
nying drawings, wherein—

Figure 1 is a perspective view of the invention
45 with the sides of the operator's chair
closed, showing the other essential features
in readiness to be operated. Fig. 2 is a per-
spective view of the invention with the sides
50 of the operator's chair open. Fig. 3 is a de-
tail perspective view looking at the under
side of the operator's chair.

Making renewed reference to the accompa-
nying drawings, wherein similar reference
55 characters indicate the corresponding parts
in the several illustrations by figures, 1 desig-
nates the floor of the operator's office, having
the usual operator's table 2 thereon, upon

which table is the usual telegraph instru-
ment 3, and said telegraph instrument is
mounted upon the farther side of the table, in
which case the tray 4 would lie in front of said
60 instrument. Said tray is hinged to the side
of the order-box 5, which is securely fastened
to one end of the table 2, as shown clearly in
Figs. 1 and 2 of the drawings. Mounted in
the correct position in front of the table is the
65 operator's chair 6, which is securely fastened
to the floor, as at 7, and also having folding
sides, which are hinged, as shown at 8, and
having a spring-actuated means 9 to securely
hold the sides of the chair open, as shown
70 clearly in Fig. 4 of the drawings. Projecting
from each side of the supporting-leg of the
chair, as at 10, are suitable pulleys 11, which
are adapted to have engaged therewith a suit-
able rope 12, the ends of which are securely
75 fastened to arms 13, projecting from the un-
der edge of the folding sides, which is clearly
illustrated in Fig. 4 of the drawings. Con-
nected to the rope 12, as at 14, is a suitable
cable or rope 15, which is adapted to pass over
80 a pulley 16, projecting from the under side of
the flooring 1. Said rope or cable 15 is adapt-
ed to pass over another pulley 17, mounted at
the other end of the flooring and projecting
85 from the under side of said flooring substan-
tially at the meeting-point of the floor and the
vertical wall of the room. Said cable 15 is
then adapted to pass through the flooring ad-
jacent to the side wall of the room to and over
90 a pulley 18, which is securely fastened to the
ceiling of the room, as shown in Fig. 1 of the
drawings. Branching from said cable 15, as
at 19, is a series of ropes or cables 20, which
are securely fastened to the levers 21, which
95 are pivoted, as at 22, to the side wall, as
shown in Fig. 1 of the drawings. Connected
to the ends of the levers 21 are suitable ropes
or cables 23, having hook devices 24, which
are adapted to engage an eye 25 upon the
100 front edge of the order-box 5—that is, when
the operator wishes to display white upon the
signaling device.

Attached to the tray 4, as at 26, is a rope
or cable 27, which passes over a pulley 28
and then over another pulley, to which it is
105 connected at the branching point of the
ropes 20, as at 19, as shown in the accom-
panying drawings. Secured at the upper
part of the side wall, or substantially at the
meeting-point in the ceiling of the side wall,
110 is a pair of guideways 30, having integral
therewith a shield or cover 31, which is

adapted to hide the color of the signaling-slide 32. Said slide 32 is provided with a rope or cable 33, which is attached, as at 34, and adapted to pass over a pulley 35 and 5 then over another pulley 36, after which it is connected, as at 37, to the cable or rope 15.

The operation of the device is as follows: For example, as the operator comes on duty he will find the hook device connected to the 10 eye 25, which will of course hold the tray in vertical position and the operator's chair closed and at the same time display the color white. In this case it will be necessary for the operator to open his chair before he 15 can get into a correct position to operate the telegraph instrument for the purpose of copying an order and while in this position he takes an order and for some cause he forgets it and goes to pull a signal-board when the 20 train for which this order is intended calls for signal, which will cause the tray to stand substantially vertical, which will slide the forgotten order in the box, which will cover the eye to which the hook device is intended 25 to be connected, which would of course remind the operator of his oversight. Train-order signals are supposed to display red at all times while the operator is on duty unless changed to white for a train to pass for which 30 he has no orders.

In practical use the train-order board or signal is adapted to be connected to the semaphore in the usual manner; but as far as this application is concerned this connection 35 forms no part of the present invention.

Of course it is distinctly understood that changes may be made in the proportions and details of construction and combination of parts without in any way departing from the 40 spirit and scope of the invention.

Having thus fully described my invention, what I claim as new, and desire to secure by Letters Patent, is—

1. In a device of the character described, 45 the same comprising an operator's chair, having collapsible sides, an operator's table, a

hinged tray to coöperate therewith, and cable connections between the chair and tray to cause said tray and chair to operate in unison.

50

2. An attachment for train-order board signal systems, comprising an operator's chair, having collapsible sides, spring-actuated means therefor, an operator's table, a hinged tray to coöperate therewith, and cable and pulley devices connected between said tray and chair to cause the same to operate in unison.

55

3. An attachment for train-order board signal systems, comprising an operator's chair, having collapsible sides, an operator's table, an order-box secured to one end of said table, a tray to coöperate between said box and said table, cable and pulley devices between said tray and said chair to cause the 65 same to be operated in unison, hook devices at each end of each cable, and an eye to coöperate with said hook devices to hold the sides of the chair in collapsed position.

60

4. An attachment for train-order board signal systems, comprising an operator's chair, having collapsible sides and spring-actuated means therefor, an operator's table, a train-order box, a tray to coöperate between said order-box and said table, and cable and 75 pulley devices to coöperate between said tray and said chair to cause the same to be operated in unison.

70

5. An attachment for train-order board signal systems, comprising in combination 80 with an operator's chair, having collapsible sides, an operator's table, a hinged tray to coöperate therewith, and cable connections between the chair and tray to cause said tray and chair to operate in unison.

85

In testimony whereof I have hereto affixed my signature in the presence of two witnesses.

JULIUS ERYC ADAIR.
